UNITED STATES PATENT OFFICE.

GEORGE E. GOODRIDGE, OF READING, MASSACHUSETTS, ASSIGNOR, BY MESNE ASSIGNMENTS, TO ARTHUR H. BALLARD, INCORPORATED, OF BOSTON, MASSACHUSETTS, A CORPORATION OF MASSACHUSETTS.

ROTARY PUMP.

Application filed July 7, 1928. Serial No. 120,952.

This invention relates to rotary pumps which may be used for pumping a great variety of liquids and gases or a mixture of the two. This type of pump may be particularly useful in connection with an oil burning system for pumping oil or oil and air to the burner.

Among the objects of the invention are: To provide a pump in which the wear may be taken care of and compensated for without the use of expensive apparatus; to provide an extremely noiseless pump such as would not be objectionable in the event of its use in connection with domestic oil burner installations; to eliminate knocking; to provide an accurate and sensitive control on the output of the pump without varying the speed of the driving means; to provide a means for preventing leakage from the pump without the use of packing; to provide positive means for keeping the blades in contact with the side walls of the pump chamber which means are not liable to get out of order and which are simple to construct and effective in operation; to provide blades which are reversible so that the pump may be taken apart and assembled by unskilled persons without rendering it inoperative; to provide an arrangement and design of the parts of the pump that will tend to equalize the wear of the blades; and generally to improve the efficiency of construction and use of pumps of this character.

Further objects and advantages of the present construction will be apparent as the description proceeds and will be specifically pointed out in the appended claims.

In the drawings in which are shown the details of certain embodiments of my invention by way of example,

Fig. 1 is an end elevation viewed from the left side of Fig. 2;

Fig. 2 is a side elevation of the device;

Fig. 3 is a central, sectional elevation showing one end of a pump embodying a modified construction;

Fig. 4 is a transverse section taken on the line 4—4 of Fig. 5;

Fig. 5 is an axial section taken on the line 5—5 of Fig. 4;

Fig. 6 is a development of a portion of the sleeve which lines the pump casing; and

Fig. 7 is an exaggerated diagrammatic

sectional view of a part of the device to show the operation.

The pump may comprise a central casing which may be provided at either end with end closure plates 2 and 3 attached to the casing 1 in any suitable manner, as, for example, by means of bolts 4. These bolts may be inserted loosely through holes in the end plates 1 and 2 and screwed into the casing 1. By making the holes in the end plates slightly larger than the bolts the position of the casing 1 may be shifted relatively to one or both of the end plates to compensate for wear and to adjust the rotor, which is journaled in suitable bearings in the end plates, accurately within the casing. It is to be understood, however, that any other desired means for so adjusting the bearings relatively to the central casing may be employed. End plates 2 and 3 may be provided with feet 5 and 5' for supporting the pump or with any other suitable means of support.

Due to the friction which is necessarily incident to packing for the shafts of pumps and other devices, it is desirable to use as little of this packing as possible to obtain the maximum mechanical efficiency. For this purpose one end plate of the pump may be provided with a closed end bearing for the rotor thus wholly doing away with packing at that point. In this instance end plate 2 is shown provided with an integral boss 6 which may be additionally supported by an integral vertical strengthening rib 7 from the foot 5'. The boss 6 is provided with a bore 8 running part way in from the face thereof which contacts with casing 1, the bore terminating in an enlarged portion 9, which may be provided with any suitable means for lubrication (not shown).

In order to eliminate the packing on the other bearing for the shaft 10 and at the same time to prevent leakage along the shaft of oil or other fluid being pumped, it has been found advantageous to connect a portion of the bearing at or around the shaft with the suction side of the pump. In the event that oil is being pumped this is practically advantageous for the reason that oil which might tend to leak out along the shaft will lubricate the bearing and then be drawn into the suction side of the pump without

the provision of other lubricating means for the bearings. It is also desirable in pumps which are adapted to be driven by a substantially constant speed drive to have some means of controlling the fluid output of the pump. This may advantageously be done by providing a valve controlled by-pass between the inlet and outlet passages of the pump. In the present device both of these objects are accomplished by practically a single integral device which is incorporated in the end plate 3. The pump casing 1 (see Fig. 4) is provided with an inlet passage 11 and an outlet passage 12 which may be connected to any suitable supply and delivery points by pipes 13 and 14 respectively. One or both of these passages may be provided with angular passages such as is shown, for example, at 15 for other or additional inlet or outlet pipes as desired. When not being used, the additional passages may be closed by screw plugs as shown at 16. The inlet and outlet ducts have connected to them (see, Figs. 1 and 2) comparatively small ducts 17 and 18 respectively extending axially of the pump, which ducts have portions in the casing 1 and other portions in the end plate 3 which portions register with each other. The end plate 3 may be provided with suitable raised or thickened portions to accommodate the ducts 17 and 18 and also those to be described. These ducts terminate in chambers in the end plate 3 which are provided at their lower portions with conical seats 21 and 22 respectively. Valves 23 and 24 are adapted to fit in seats 21 and 22 respectively and may be controlled in any suitable manner, as, for example, by screw bolts 25 and 26 respectively integral therewith which may be provided with any desired means for turning them, as, for example, the screw driver slots shown. The end plate 3 is provided with a boss 27 which may be supported by a rib 28 in a similar manner to boss 6 and rib 7 described above. The boss 27 is provided with a bore 29 extending completely therethrough, the whole forming a bearing for that part of the shaft 10. In Figs. 1 and 2 there is shown within the boss 27 and surrounding the bore 29 an annular groove 30 which is connected by passages 31 and 32 with the valve chambers below the valve seats thereof.

The operation of the device thus far described is as follows: In the event that it is desired to cut down the output of the pump, both the valves 23 and 24 are opened to bypass a desired amount of the fluid being pumped from the outlet of the pump to the inlet. However, if it is not desired to cut down the output in this way, the valve 24 connecting the groove 30 in the bearing to the outlet side of the pump is closed. Normally the valve 23 connecting the groove 30 to the inlet side of the pump is open. This

will connect the groove 30 through the passage 31, valve chamber and passage 17 to the inlet chamber 11 where a suction exists which will draw into the inlet chamber of the pump any of the fluid being pumped which might otherwise escape along the shaft 10. In practical operation valve 23 will be maintained open during all the time the pump is in use so that a continuous suction is maintained on the bearing and valve 24 only open to a slight extent when it is desired to by-pass a portion of the fluid being pumped. The valve 23 is only closed when the pump is shut down so as to prevent any fluid which might be in the inlet chamber of the pump from leaking out along the shaft and causing a possible fire risk in the case of a pump for oil.

Figure 3 shows a modification of the device illustrated in Figs. 1 and 2, and in particular shows a modified form of end plate 3' which is provided with a boss 27' which in turn provides a bearing for the shaft 10, as in the first described construction. In this modification, however, the inlet pipe 13' is connected to the bottom of an inlet chamber comprising a circumferential groove or enlargement 33 entirely surrounding the rotor shaft 10. This inlet chamber 33 is connected to the suction chamber of the pump by means of the axially extending passage 34, the radial passage 35, and the communicating, axially extending passage 35' opening into the suction chamber. A valve controlled by-pass from the outlet side of the pump to the suction passage 35, similar to that described in connection with Figs. 1 and 2, may be employed if desired, or the construction of Fig. 3 may be employed without such by-pass. Accordingly, as the pump is rotated the liquid fuel is drawn under suction into the inlet chamber 33 about the bearing portion of the rotor shaft and into the suction chamber of the pump and delivered under pressure through the delivery pipe 14. During such time as the pump is in operation there is no tendency for the oil or other liquid employed to escape from the end plate 3' about the rotor bearings, and when the operation of the pump is stopped any residual liquid in the suction chamber will drain back into the suction pipe. Accordingly, it is possible to operate the pump as so constructed without the necessity of packing for the rotor bearings.

The pump casing is provided with a substantially cylindrical chamber which in the present instance is provided with a substantially cylindrical sleeve or lining member 36. The inlet passage (either 11 in Fig. 4 or 35' in Fig. 3) may be connected to a substantially arcuate chamber 37 extending almost from end to end of the casing 1 of the pump and slightly less than 90° about its periphery. Outlet chamber 12 is pro-

vided with a substantially similar arcuate chamber 38. The lining member 36 which is shown extended on Fig. 6 is provided with a plurality of small staggered openings, certain of which are arranged in parallel rows 39 and 40 on either side of and closely adjacent to a dividing wall 41 between chambers 37 and 38. The remainder of the openings from and to the inlet and outlet chambers respectively are situated fairly evenly over the whole area of these chambers. This arrangement of holes is for the purpose of providing at all times a substantial support for the blades, as a single elongate opening would permit the blades to wear to a greater extent on the ends which would eventually cause the portion of the blade opposite the opening to drop into it on each revolution and cause knocking and irregular operation.

20 A rotor 42 is mounted in any suitable manner upon the shaft 10 and may be integral therewith. This rotor is provided with two or more radial slots 43 extending from end to end thereof. In the present embodiment two slots are shown diametrically opposite each other, this being the preferred construction. The slots 43 are adapted to hold blades 44 loosely slidably therein.

Means are provided for holding the blades in engagement with the inside of the sleeve member 36, such means in the present case taking the form of a cup member 45 and a plug member 46 having a part extending loosely into the cup member 45, members 45 and 46 being urged apart by a suitable compressible member, as, for example, a spiral spring 47 arranged wholly within the cup 45. These members are adapted to be contained in suitable bores extending between the slots 43 and preferably substantially perpendicular to the axis of the rotor. It has been found by experiment that this form of device for urging the plates against the sides of the casing is very satisfactory for the reason that the spring or other extensible device is entirely enclosed and the hole is not liable to get stuck or out of order, and furthermore, the parts are protected against dirt and other foreign material lodging therein.

An important feature is the provision for eliminating that noise which manifests itself in pumps of this type by a "knocking" effect. The line of tangency 50 between the eccentrically mounted rotor 42 and the lining, at the dividing wall 41, provides a seal between the inlet and outlet chambers of the pump, across which the motor blades move with a wiping action.

80 Since the rotor contacts with the walls of the pump chamber substantially in a single line of tangency, which is separated by an appreciable distance from the nearest edge of the outlet 40, there is formed between the outlet port and the line of tangency a small

clearance space bounded by the inner surface of the lining and the outer surface of the rotor, which space gradually decreases in size as it approaches the line of tangency where the walls of the lining and the rotor converge.

In pumps of this type as heretofore constructed, the effect produced by the blade in closing the outlet opening is to close also this small clearance space, trapping therein a small quantity of the oil or other liquid being pumped. The trapped liquid thus becomes confined in a closed space of triangular like cross section bounded by the advancing face of the blade, by the outer surface of the rotor, and by that part of the inner surface of the lining located between the line of tangency and the wiping edge of the blade. With the continuing advance of the blade from the outlet port toward the line of tangency, the volume of this space confining the trapped liquid becomes progressively less and entirely disappears as the blade reaches the point of tangency. The pressure on this trapped liquid accordingly increases as the blade approaches the point of tangency and is not relieved until the blade releases the liquid to the suction side of the pump. The liquid, being substantially incompressible, must seek relief from this increasing pressure, and this it appears to do by forcing the blade inwardly. During the interval which elapses therefore between the time the blade closes the discharge opening and the time it crosses the seal and releases the trapped liquid to the suction side, the liquid is placed under rapidly increasing pressure and is then suddenly released, the apparent effect being to cause the blade to move inwardly and then outwardly, but at all events producing a knock which is repeated each time one of the blades wipes over the seal.

In the pump herein described, I have arranged the parts, including the relative proportions of the seal and the blade, so that the liquid caught or trapped in advance of the blade on the compression side of the seal is released to the suction side of the pump just before the wiping or contacting edge of the blade reaches the point where it is effective in cutting off such trapped liquid from the ports on the compression side, whereby such liquid is not subjected to the pressure referred to and the noise or knocking described is thereby suppressed.

This result may be secured by various different relative arrangements of the blade, partition wall and rotor, but herein, as illustrative of the broad principle, I have provided a simple but effective construction. To this end the blade 44 has its advancing end at 48 beveled or rounded on a sharp radius of curvature, so that when the blade approaches the seal and retreats within its

slot, there is provided a small, substantially triangular recess or pocket in advance of the contacting edge of the blade, which recess is formed between the rounded edge of the 5 blade, the wall 51 of the slot 43 and the lining sleeve 36. Preferably the blade is beveled or rounded from its contacting edge in both directions, forwardly and rearwardly, and the blade, moreover, is of a thickness 10 greater than that of the partition wall between the inlet and outlet openings. Accordingly, the distance from the contacting or effecting wiping edge of the blade and the side wall 51 of the slot 43 is greater than 15 that between the point of tangency 50 and the edge 49 of the outlet opening.

As the rotor turns (right-handedly in Fig. 4), the advancing face of the blade and the wall 51 (see Fig. 7) of the slot 43 20 pass the point of tangency 50 before the contacting or effective wiping edge of the blade reaches the point 49 and before it seals off the outlet chamber of the pump to the liquid which is caught in advance of the contacting 25 edge and in the triangular recess referred to. Since the wall 51 of the slot 43 has then passed the point of tangency, and the periphery of the rotor at the end of the wall 51 is then spaced a short distance from 30 the sleeve 36, the trapped liquid is thereby provided with an outlet to the suction side of the pump before it is completely cut off from the compression side and, accordingly, will pass into the suction side and be recirculated 35 through the pump.

By a proper selection of clearances, this slight leakage may be reduced to an unsubstantial amount, but it results in a marked reduction in the pounding noise incident 40 to the operation of the pump, which noise is due mainly to the pressure exerted on the small confined slug of oil if the outlet opening is closed before the point of tangency is reached.

45 While I have shown and described certain definite embodiments of the invention, I do not wish to be limited to the shape, size, design or construction of the embodiment shown but merely by the scope of the appended claims.

Claims:

1. A rotary fluid pump comprising a casting having a substantially cylindrical chamber therein, a rotor mounted eccentrically of 55 said chamber, one or more pairs of diametrically opposite radial slots in said rotor, blades in said slots, transverse bores connecting said slots and expansible members in said bores and exerting an upward pressure 60 on said opposite blades, each of said expansible members comprising a cup member having a compressible member therein and a plug member having a part fitting into said cup member and resting against said compressible member.

2. A rotary fluid pump comprising a casting having a substantially cylindrical chamber therein, a rotor mounted eccentrically of said chamber, one or more pairs of diametrically opposite radial slots in said rotor, 70 double edged reversible blades in said slots, transverse bores connecting said slots and expansible members in said bores and exerting an upward pressure on said opposite blades, each of said expansible members comprising a cup member having a compression spring therein and a plug member having a part fitting into said cup member and resting against said compressible spring to be urged outwardly thereby. 75

3. A rotary fuel pump having inlet and outlet chambers, a cylindrical pump chamber communicating with said inlet and outlet chambers, a rotor eccentrically mounted within said pump chamber and contacting with the pump chamber between the inlet and outlet chambers to form a seal thereat, a blade carried by said rotor and adapted to wipe over the inner surface of said cylindrical pump chamber, whereby said blade in 90 wiping over the outlet side of the seal carries before it a small amount of fluid, and means for relieving the increasing compression on said small amount of fluid by releasing the same to the inlet side of the seal before the blade closes the compression side thereto. 95

4. A rotary fluid pump comprising a casting having inlet and outlet chambers, a central cylindrical chamber to which the inlet 100 and outlet chambers open, a rotor eccentrically mounted within said central chamber and tangent to a line thereof to form a seal thereat, a blade in said rotor, said blade, rotor and seal being related to each other to cause a small amount of the fluid being pumped to be carried past the point of tangency to the inlet side before closing the outlet opening on each revolution of the pump, whereby to prevent knocking. 105

5. A rotary fluid pump having inlet and outlet chambers, a central, cylindrical pump chamber, a rotor eccentrically mounted within the pump chamber and substantially tangential thereto at a line between the inlet 110 and outlet thereof, a blade carried by the rotor and adapted to wipe over the inner surface of the cylindrical pump chamber, the blade acting to carry a small amount of fluid past the outlet port before the latter is cut off by the wiping edge of the blade, and the distance from the inlet port to the point of tangency being such as to release said fluid to the inlet side of the pump before the blade cuts off said outlet port. 115

6. A rotary fluid pump having inlet and outlet chambers, a central, cylindrical pump chamber, a rotor eccentrically mounted within the pump chamber and substantially tangential thereto at a line between the inlet 120 and outlet thereof, a blade carried by the rotor and adapted to wipe over the inner surface of the cylindrical pump chamber, the blade acting to carry a small amount of fluid past the outlet port before the latter is cut off by the wiping edge of the blade, and the distance from the inlet port to the point of tangency being such as to release said fluid to the inlet side of the pump before the blade cuts off said outlet port. 125

- and outlet ports thereof, a blade carried by the rotor and adapted to wipe over the inner surface of the cylindrical pump chamber, a slot in said rotor in which said blade slides, the advancing portion of the edge of said blade being beveled or rounded back from its face toward its contacting or wiping portion, and the distance from the advancing face to the wiping or contacting portion of its edge being greater than the distance from the outlet port to the point of tangency. 50
7. A rotary fluid pump having inlet and outlet chambers, a central, cylindrical pump chamber, a rotor eccentrically mounted within the pump chamber and substantially tangential thereto at a line between the inlet and outlet ports thereof, a blade carried by the rotor and adapted to wipe over the inner surface of the cylindrical pump chamber, a slot in said rotor in which the blade slides, said blade and rotor being related to form a pocket or recess in advance of the effective wiping edge of the blade when the latter is in its retreated position, the distance from the effective wiping edge of the blade to the leading end of said recess being greater than the distance from the outlet port to the point of seal. 55
8. A rotary fluid pump comprising a casing having a substantially cylindrical chamber therein, an inlet chamber and an outlet chamber communicating with said cylindrical chamber, a wall therebetween parallel with the axis of said cylindrical chamber, a rotor mounted eccentrically within said casing, said rotor being tangent to the inside of said cylindrical chamber along a line between the inlet and outlet chambers to form a seal thereat, a slot in said rotor and a blade in said slot, the distance between the edge of the outlet chamber adjacent the point of tangency and said line being less than half the width of the blade. 60
9. A rotary fluid pump comprising a casing having a substantially cylindrical chamber therein, an inlet chamber and an outlet chamber communicating with said cylindrical chamber, a wall therebetween parallel with the axis of said cylindrical chamber, a rotor mounted eccentrically within said casing, said rotor being tangent to the inside of said cylindrical chamber along a line between the inlet and outlet chambers to form a seal thereat, a slot in said rotor and a blade in said slot, the distance between the edge of the outlet chamber adjacent the point of tangency and said line being less than half the width of the blade. 65
10. A rotary pump comprising a casing, a rotor mounted eccentrically within said casing but contacting therewith, inlet and outlet chambers on opposite sides of said region of contact, blades in said rotor, each blade having its edge rounded to provide substantially a line of contact with the inner wall of said casing, the radius of curvature of the end of the blade being short to provide a small fluid pocket between the contacting part of the blade, the side walls of the slot and the enclosing cylindrical casing and each blade being wider than the space between the inlet and outlet chambers. 70
11. A rotary liquid pump having a casing containing a pump chamber, a rotor shaft provided with a bearing adjacent said pump chamber, said casing having a liquid suction chamber and a liquid discharge chamber, a suction space to which the bearing portion of the shaft in said casing is exposed, said space being connected with the liquid suction chamber by a suction conduit, and an inlet chamber adapted for connection to an extraneous source of liquid supply and connected to said suction chamber through said suction space and said suction conduit. 75

In testimony whereof, I have signed my name to this specification.

- and outlet ports thereof, a blade carried by the rotor and adapted to wipe over the inner surface of the cylindrical pump chamber, a slot in said rotor in which said blade slides, the advancing portion of the edge of said blade being beveled or rounded back from its face toward its contacting or wiping portion, and the distance from the advancing face to the wiping or contacting portion of its edge being greater than the distance from the outlet port to the point of tangency. 50
7. A rotary fluid pump having inlet and outlet chambers, a central, cylindrical pump chamber, a rotor eccentrically mounted within the pump chamber and substantially tangential thereto at a line between the inlet and outlet ports thereof, a blade carried by the rotor and adapted to wipe over the inner surface of the cylindrical pump chamber, a slot in said rotor in which the blade slides, said blade and rotor being related to form a pocket or recess in advance of the effective wiping edge of the blade when the latter is in its retreated position, the distance from the effective wiping edge of the blade to the leading end of said recess being greater than the distance from the outlet port to the point of seal. 55
8. A rotary fluid pump comprising a casing having a substantially cylindrical chamber therein, an inlet chamber and an outlet chamber communicating with said cylindrical chamber, a wall therebetween parallel with the axis of said cylindrical chamber, a rotor mounted eccentrically within said casing, said rotor being tangent to the inside of said cylindrical chamber along a line between the inlet and outlet chambers to form a seal thereat, a slot in said rotor and a blade in said slot, the distance between the edge of the outlet chamber adjacent the point of tangency and said line being less than half the width of the blade. 60
9. A rotary fluid pump comprising a casing having a substantially cylindrical chamber therein, an inlet chamber and an outlet chamber communicating with said cylindrical chamber, a wall therebetween parallel with the axis of said cylindrical chamber, a rotor mounted eccentrically within said casing, said rotor being tangent to the inside of said cylindrical chamber along a line between the inlet and outlet chambers to form a seal thereat, a slot in said rotor and a blade in said slot, the distance between the edge of the outlet chamber adjacent the point of tangency and said line being less than half the width of the blade. 65
10. A rotary pump comprising a casing, a rotor mounted eccentrically within said casing but contacting therewith, inlet and outlet chambers on opposite sides of said region of contact, blades in said rotor, each blade having its edge rounded to provide substantially a line of contact with the inner wall of said casing, the radius of curvature of the end of the blade being short to provide a small fluid pocket between the contacting part of the blade, the side walls of the slot and the enclosing cylindrical casing and each blade being wider than the space between the inlet and outlet chambers. 70
11. A rotary liquid pump having a casing containing a pump chamber, a rotor shaft provided with a bearing adjacent said pump chamber, said casing having a liquid suction chamber and a liquid discharge chamber, a suction space to which the bearing portion of the shaft in said casing is exposed, said space being connected with the liquid suction chamber by a suction conduit, and an inlet chamber adapted for connection to an extraneous source of liquid supply and connected to said suction chamber through said suction space and said suction conduit. 75

In testimony whereof, I have signed my name to this specification.
